GESELLSCHAFT, OF SIEMENSSTADT, NEAR BERLIN, GERMANY

TELEPHONE SYSTEM

Application filed January 2, 1931, Serial No. 506,024, and in Germany February 22, 1930.

The invention relates to a circuit arrangement for telephone systems in which conversational switches are controlled by setting switches allocated in common to a plurality of conversational switches.

One object of the invention is, in systems where the allocation of setting switches common to a plurality of conversational switches is effected over auxiliary switches to decrease the number of wipers in these auxiliary switches, which in order to make possible a control of conversational switches by setting switches, must correspond to the number of line groups located in the conversational switch, this being achieved by auxiliary switches controlled by conversational switches being associated with the setting switches.

Another object of the invention is to decrease, as far as possible, the number of switching devices individually associated with the conversational switches and this is achieved in this manner that a movement (caused by the commonly associated switching devices) of the conversational switch used for a connection to the normal position is effected, for the purpose of a fresh seizure of the conversational switch, only after a succeeding connecting operation by the common switching devices.

A further object of the invention is to make possible, at the setting up of a connection, only one seizure of the same conversational switch which is in the condition suitable for the setting up of the connection in the moment of its seizure. This is achieved in this manner, that, at the setting up of a connection, only conversational switches can be seized to which switching devices, operating the driving magnet, have been connected over auxiliary switches.

An embodiment of the invention is shown in the drawing.

A subscriber T_{n1} is seen who, over a pre-selector VW , can influence further numerical impulse receivers succeeding this pre-selector, namely IGW , $IIGW$ and LW for the setting up of a connection with the subscriber T_{n2} .

Only the setting circuit for the numerical

impulse receiver $IIGW$ is shown in the diagram. A setting of the further numerical impulse receivers can take place in any known manner.

The numerical impulse receiver $IIGW$ is only set in one directional movement (rotation) and in such a manner that the line group is marked by setting switches in which the conversational switch in the numerical impulse receiver $IIGW$ then hunts for a free line.

The setting switch and a further auxiliary switch, for the establishment of the connection is placed at the disposal of the conversational switch over a connecting switch.

In detail the connecting operations are as follows:

When the subscriber T_{n1} lifts his receiver, the preselector VW hunts freely for a succeeding numerical impulse receiver, e. g. IGW in known manner. An energizing circuit for relay C is completed over the third wiper of the preselector VW , while relay A is energized over the line loop of the subscriber T_{n1} in the circuit: earth, battery, winding I of relay A , wiper of preselector VW , a -lead, subscriber T_{n1} , b -lead, wiper of preselector VW , winding II of relay A , earth.

By the transmission of numerical current impulses, e. g. the intermittent breaking of the energizing circuit for relay A , the numerical impulse receiver IGW can be set to the required line group in any known manner. It hunts freely in this group for a succeeding numerical impulse receiver and reaches, for example, the numerical impulse receiver $IIGW$ on which a connecting switch is set so that relay P of the connecting switch is energized over: earth, contact $6c1$, wiper $a1$ of the connecting switch, windings I and II of relay P , resistance W_{i3} , battery, earth.

At the seizure of the numerical impulse receiver the following circuit is completed: earth, resistance W_{i2} , wiper c of the numerical impulse receiver IGW , rotary off-normal contact w of the conversational switch, wiper $a6$ of the connecting switch, contact $20p$, rotary off-normal contact $21we$ of the setting switch, $22wh$ of the auxiliary switch, relay $V2$, battery, earth. In this circuit relay $V2$

is energized and connects the rotary magnet D_e of the setting switch to a speaking lead of the junction line by the closing of contact 31v2 and places relay C2 in this engaging circuit by the closing of contact 19v2.

When the subscriber T_{n1} sends out the next impulse series, the rotary magnet D_e is energized over: earth, contacts 2c1, 1a, 38c1, wiper a7 of the connecting switch, contact 31v2, 10 rotary magnet D_e of the setting switch, battery, earth. Corresponding to the impulse series the wiper de is, by way of example, set to contact 2 of its contact bank. After the first rotary step of the setting switch the forward switching of the conversational switch is effected by its rotary magnet D being influenced over: earth, battery, rotary magnet D , contact 4c1, wiper a2 of the connecting switch, contacts 13c2, 12t2, contact 11dh of 15 the auxiliary switch, influenced by the rotary magnet D_h , contact 10t1, relay interrupter RU1, earth.

At the forward switching, the switch shaft of the conversational switch operates a contact 15w in such a manner that this contact, 25 when reaching the last contact of each individual line group, closes a circuit for relay T2. In the present case, contact 15w is operated after the conversational switch has 30 run through the ten contacts of the first line group (when the second line group is required) and this causes the energization of relay T2. Hereby a further energization of the rotary magnet D of the conversational switch is prevented at contact 12t2. In addition the rotary magnet D_h of the auxiliary switch is influenced by the closing of contact 25t2, with the result that its wiper dh is set 35 on contact 2 after a rotary step. In this 40 switching position an energization of relay T1 is completed, over: earth, battery, resistance Wi_6 , contact 36v2, relay T1, wiper de of the setting switch, contact 2, wiper dh of the auxiliary switch, earth. The contact 45 41dh, operated at the energization of the rotary magnet D_h , produces an impulse to operate the rotary magnet D of the conversational switch over: earth, rotary magnet D , contacts 4c1, wiper a2 of the connecting 50 switch, 13c2, 42t2, 41dh, earth. The conversational switch moves one step so that 15w is opened and relay T2 thereby deenergized. After the deenergization of relay T2 the rotary magnet D_h of the auxiliary switch is 55 also deenergized. After relay T1 has also been deenergized by the opening of the contact 36v2 after the termination of the impulse series, the rotary magnet D of the conversational switch receives a new impulse over: 60 earth, battery, rotary magnet D of the conversational switch, contact 4c1, wiper a2 of the connecting switch, contacts 13c2, 12t2, 11dh, 10t1, RU1, earth.

The conversational switch now hunts freely in the reached line group for a free line,

for example, such a line that leads to the numerical impulse receiver LW. When this has been reached, the following circuit is completed: earth, battery, resistance Wi_7 , wiper c of the conversational switch, wiper a8 of the connecting switch, contacts 32c2, 33t2, 35v2, relay T1, wiper de of the setting switch, contact 2, wiper dh of the auxiliary switch, earth. Relay T1 now responds. By the opening of contact 10t1 the rotary magnet of the conversational switch is brought to rest, causing the relay P to deenergize by short circuiting, over contacts 7v2 and 8t1, so that, by the short circuiting of the high resistance winding of relay C2 over contact 17p, an energization of relay C1 is caused over: earth, resistance Wi_2 , c-wiper of the numerical impulse receiver IGW, winding I of relay C1, wiper a4 of the connecting switch, contacts 16c2, 17p, resistance Wi_4 , battery, earth. By the closing of contacts 3c1 relay C1 connects itself with its winding II in a locking circuit.

After the deenergization of relay C2, the auxiliary switch D_h is now brought to its normal position by the energization of its rotary magnet over: earth, battery, rotary magnet D_h of the auxiliary switch, rotary off-normal contact 43wh of the auxiliary switch, contact 27c2, relay interrupter RU2, earth. When the auxiliary switch has reached its normal position, the setting switch is brought to its normal position over the now closed rotary off-normal contact 26wh in the following circuit: earth, battery, rotary magnet D_e , rotary off-normal contacts 30we, 26wh, contact 27c2, RU2, earth. When these switches have reached their normal positions, the connecting switch is connected up to the next conversational switch, not taken into use, by its rotary magnet Da being energized over: earth, battery, rotary magnet Da , contact 28p, rotary off-normal contact 29we, of the setting switch, 26wh of the auxiliary switch, contact 27c2, relay interrupter RU2, earth. When the connecting switch finds a conversational switch, not taken into use, relay P is energized in the circuit corresponding to the following: earth, contact 6c1, wiper a1 of the connecting switch, windings I and II of relay P, resistance Wi_3 , battery, earth. By the opening of contact 28p the connecting switch is brought to rest on the reached conversational switch.

After the above described setting of the numerical impulse receiver IGW to the numerical impulse receiver LW, the subscriber can, by transmission of further impulses, connect himself to the required subscriber T_{n2} . After the transmission of ringing current and reply by the subscriber the connection with the required subscriber T_{n2} is established.

The release of the switches, after the con-

versation is ended, is of no interest in the present case as it can be effected in any known manner.

What is claimed is:

5. 1. In an automatic telephone system, an incoming trunk line, an outgoing trunk line, a first switch for interconnecting said trunk lines, a second switch directly controlled by impulses to mark a particular contact, automatic means for stepping said first switch, a third switch controlled at predetermined intervals by said first switch, cam springs in said first switch for effecting said control over said third switch, and means operative responsive to said third switch and said second switch being positioned to corresponding contacts for stopping the automatic stepping of said first switch. 70
2. In an automatic telephone system, an incoming trunk line, an outgoing trunk line, a first switch for interconnecting said trunk lines, a second switch directly controlled by impulses to mark a particular contact, automatic means for stepping said first switch, a third switch controlled at predetermined intervals by said first switch, means operative responsive to said third switch and said second switch being positioned to corresponding contacts for stopping the automatic stepping of said first switch, and a fourth switch automatically controlled for connecting said second and third switch with said first switch. 75
3. In an automatic telephone system, a plurality of switches for completing connections, a common control equipment for controlling any one of said plurality of switches, a connecting switch individual to said common control equipment, and means associated with said common control equipment for controlling said connecting switch to select an idle one of said plurality of switches and for making the selected switch seizable over its incoming trunk. 80
4. In an automatic telephone system, a plurality of switches, a common control equipment for controlling any one of said switches to establish a telephone connection, means for connecting said common control equipment with an idle one of said switches to make it selectable over its incoming trunk, and means for disconnecting said common control equipment from said switch after a connection is completed, said switch being maintained busy over its incoming trunk and held in its operated position after the release of said connection. 85
5. In an automatic telephone system, a plurality of switches, a common control equipment for controlling any one of said switches to establish a telephone connection, means for connecting said common control equipment with an idle one of said switches to make it selectable over its incoming trunk, and means for disconnecting said common control equipment to an idle one of said first switches, means 90
- trol equipment from said switch after a connection is completed, said switch being maintained busy over its incoming trunk and held in its operated position after the release of said connection, and means operative when said common control equipment is again connected to said switch for restoring it to its normal position to make it selectable over its incoming trunk. 95
6. In an automatic telephone system, a first switch, a setting switch, means for positioning said setting switch, means for automatically stepping said first switch, an auxiliary switch, means controlled at predetermined intervals by said first switch for stepping said auxiliary switch, a circuit independent of the wipers of said first switch over which said stepping means is controlled, and means operative responsive to the wipers of said auxiliary switch and said setting switch being positioned on corresponding contacts for stopping the stepping of said first switch. 100
7. In an automatic telephone system, a first switch, a setting switch, means for positioning said setting switch, means for automatically stepping said first switch, an auxiliary switch, means controlled at predetermined intervals by said first switch for stepping said auxiliary switch, means operative responsive to the wipers of said auxiliary switch and said setting switch being positioned on corresponding contacts for stopping the stepping of said first switch, a connecting switch individual to said setting and auxiliary switches, and means automatically controlled for causing said connecting switch to be connected with said first switch. 105
8. In an automatic telephone system, a plurality of incoming trunk lines and a plurality of outgoing trunk lines, a plurality of first switches for interconnecting said incoming trunk lines with said outgoing trunk lines, common controlling equipment common to said first switches, a second switch for connecting said common control equipment to an idle one of said first switches, means operative responsive to the connecting up of said common control equipment with a said first switch over said second switch for making such first switch seizable over the associated incoming trunk line, and means operative responsive to the interconnecting of the associated incoming trunk line with one of said outgoing trunk lines for automatically disconnecting said second switch from the first switch. 110
9. In an automatic telephone system, a plurality of incoming trunk lines and a plurality of outgoing trunk lines, a plurality of first switches for interconnecting said incoming trunk lines with said outgoing trunk lines, common controlling equipment common to said first switches, a second switch for connecting said common control equipment to an idle one of said first switches, means 115
- 120
- 125
- 130

operative responsive to the connecting up of said common control equipment with a said first switch over said second switch for making such first switch seizable over the associated incoming trunk line, means operative responsive to the interconnection of the associated incoming trunk line with one of said outgoing trunk lines for automatically disconnecting said second switch from the first switch, and means operative responsive to the release of said interconnection for temporarily making the first switch unavailable over the associated incoming trunk line.

10. In an automatic telephone system, a plurality of incoming trunk lines and a plurality of outgoing trunk lines, a plurality of first switches for interconnecting said incoming trunk lines with said outgoing trunk lines, common controlling equipment common to said first switches, a second switch for connecting said common control equipment to an idle one of said first switches, means operative responsive to the connecting up of said common control equipment with a said first switch over said second switch for making such first switch seizable over the associated incoming trunk line, means operative responsive to the interconnection of the associated incoming trunk line with one of said outgoing trunk lines for automatically disconnecting said second switch from the first switch, means operative responsive to the release of said interconnection for temporarily making the first switch unavailable over the associated incoming trunk line, and means for automatically restoring the first switch to normal to make it available over the associated incoming trunk line when it is again seized by said second switch.

15. In witness whereof, I hereunto subscribe my name this 3rd day of December, A. D. 1930.

ERNST HORN.
